OTTO PETERMANN, OF NEW YORK, N. Y., ASSIGNOR, BY MESNE ASSIGNMENTS, TO
STANDARD TYPEWRITER COMPANY, A CORPORATION OF NEW YORK.

BAR MECHANISM FOR TYPE-WRITING MACHINES.

1,087,459.

Specification of Letters Patent. Patented Feb. 17, 1914.

Application filed June 12, 1909. Serial No. 501,849.

To all whom it may concern:

Be it known that I, OTTO PETERMANN, a citizen of the Republic of Switzerland, and a resident of New York, county and State of New York, have invented certain new and useful Improvements in Bar Mechanism for Type-Writing Machines, of which the following is a full, clear, and exact description.

10 This invention relates more particularly to the bar mechanism of a foldable front strike or visible typewriting machine.

The primary object of the invention is to provide simple and efficient means for independently and detachably supporting a plurality of type-bars in such a way that each type-bar may be independently removed from its support without affecting any of the other bars, and to provide simple 20 means for operating the bars so that the same may engage the platen at the front thereof to adapt the machine for visible writing.

A further object of the invention is to 25 provide a simple and efficient bracket, forming a common support for the different type-bars, and to provide a plurality of independent devices so connected and held to the bracket that the type-bars may be properly held thereto or removed therefrom as desired.

With these and other objects in view, the invention will be hereinafter more particularly described with reference to the accompanying drawings, which form a part of this specification, and will then be pointed out in the claims at the end of the description.

In the drawings, Figure 1 is a longitudinal section, partly in elevation, of one form 40 of machine embodying my invention. Fig. 2 is a detail front elevation of the bracket for supporting the type-bars. Fig. 3 is a transverse section of the bracket, and Fig. 4 is a detail perspective view of the device for 45 detachably holding one of the type-bars to the bracket.

The machine hereinafter set forth is of the type shown in the patent to Frank G. Rose, No. 754,242, patented March 8th, 1904, in which the carriage is adapted to be folded over above the keys, and while in the present invention the carriage and platen and their operating mechanisms are adapted to 55 be raised and lowered on the frame of the

machine and to be folded over above the finger keys, and in which the type-bars have a front strike for visible writing, it is to be understood that the features of this invention may be used in connection with other forms of typewriting machines.

The metallic frame 10 of the machine may be constructed and arranged in any suitable manner, and may consist of side members 11 and an integral back member, with an intermediate transverse horizontal bar 12 suitably fastened to the sides of the frame and serving as a brace therefor, and a second transverse bar 13 at the front of the machine, the whole frame being constructed of sheet metal with rounded edges for the purpose of making the frame light and strong.

The key-levers 14 may have finger pieces 15, and are each provided intermediate its ends with an upwardly-extending part 16. 25 This part 16 may be integral with the body portion and the whole lever may be stamped from sheet metal or other material for strength and cheapness. The upwardly-extending part 16 of each key-lever is 30 formed substantially U-shaped when viewed from above, so that said levers may be readily and quickly hung or supported, each by a pair of hooks, from a plurality of transversely-extending bars or members 17 35 which are located under and extend downward from the transverse bar 18, as shown best in Fig. 1. As shown there are three bars 17, and each bar is provided with an upwardly turned or hooked end 19 which is 40 adapted to fit in the notches 20 of the key-levers 14, so that said levers will be supported on substantially a knife edge and at two points some distance to each side of the body portion in substantially the same manner as set forth in my Patent No. 1,081,140, dated Dec. 9, 1913.

Each key-lever 14 is provided with an aperture on its under side in which is adapted to be fastened one end of a spring 21, and the other end of said spring is held to a projecting part 22 stamped or forced from a transverse bar 23 at the lower part of the machine whereby the said levers may be restored to their normal position. The inner ends of the levers are each provided with an aperture in which one end of a link 24 is held, and the other end of said link is pivotally held to a type-bar 25, there being a type-bar for each key-lever. These type-

bars 25 are each pivoted at 26 in a slotted part 27 of a transversely-extending and curved bracket or bar 28 which is held to the rear of the machine frame by means of 5 screws 29 or otherwise. This bracket or bar 28 may be made in a solid piece, and each type-bar has its pintle held in a slot or recess 30 and is normally held against removal by means of an angular bar or device 31. The device is L-shaped and has the 10 part 31^a horizontally arranged and its other part 31^b vertically arranged, and said vertical part is slotted at its upper end 32 to span the sides of its co-operating type-bar 25. The 15 upper edge of the end 32 is beveled and is adapted to engage the pintle 26 on opposite sides of the type-bar, and said end serves as a lower bearing for said pintle, and to hold the type-bar removably in the recess 30, the 20 said recess being formed by cutting away the bracket to form an overhanging portion. The device 31 is provided with a tongue 33 projecting from the vertical portion 31^b and which enters one of the slots 27 of the 25 bracket 28 to assist in holding the device from lateral or sidewise movement, and in addition to the tongue 33 the said device is provided with an aperture through which extends the stem of a screw 34. This screw 30 34 is adapted to engage a threaded aperture in the bracket and serves to force one part of the device against the lower surface of the bracket, the tongue 33 preventing any sidewise movement of the device. By re- 35 moving the screw 34 of each type-bar the retaining device or member 31 may be lowered sufficiently to permit any one of the type-bars 25 to be removed entirely independent of any of the other bars, or to be 40 quickly inserted therein and by proper adjustment of the screw 34 any wear that might occur may be readily taken up.

The type-bars 25 at their outer ends are each provided with a head 35, and each head 45 has a plurality of characters 36, 37 and 38, the former indicating the figures, the intermediate one the upper case, and the third the lower case. These type-bars are each adapted to rest upon a felt or other cushion- 50 ing means 39 which is supported by a transversely extending and curved plate or bar 40 suitably supported at its ends to the machine frame and said felt corresponds in its curvature to that of the bar or bracket 28 55 and to the arrangement of the type-bars.

A support or frame 41 is arranged above the machine frame, and this support is provided with extended portions 42. These extended portions are pivotally held to slides 60 43 at each rear corner of the machine, and these slides at the lower end are connected to one or more space levers 44 to adapt the slides and frame or support to be elevated. The support 41 has a carriage 45 mounted 65 to move thereon, and on the carriage is a

suitable platen 46, the means for elevating the support and carriage thus referred to being of any suitable construction and operated in any desired way.

From the foregoing it will be seen that 70 simple and efficient means are provided whereby a number of type-bars may be pivotally held to a bracket each adapted to be independently removed without affecting any of the other type-bars; that said type-bars are so mounted as to adapt the machine for visible writing; and that a simple bracket and independent devices mounted on said bracket are provided to properly hold the type-bars. 75

Having thus described my invention, I claim as new and desire to secure by Letters Patent:-

1. In a typewriting machine, the combination with a bracket having a plurality of 85 slots, of a plurality of type-bars pivotally held in said slots each with an independent pintle, said slots being open transversely for the removal of the pintle and type-bars, angularly formed devices having one end 90 adapted to engage the pintle and hold it in its slot, said device having a tongue fitting a groove in the bracket, and a screw for detachably holding each of said devices. 95

2. In a typewriting machine, the combination with a bracket having a plurality of slots, of a plurality of type-bars pivotally held in said slots each with an independent pintle, said slots being open transversely for the removal of the pintle and type-bars, angularly formed devices having one end 100 adapted to engage the pintle and hold it in its slot, said device having a tongue fitting a groove in the bracket, and means for detachably holding each of said devices to the 105 bracket.

3. In a typewriting machine, the combination with a bracket having an over-hanging portion forming open seats and a plurality of slots intersecting said over-hanging portion, of a plurality of type-bars pivotally held in said slots each provided with an independent pintle adapted to rest in said seats on opposite sides of its type-bar slot, and angularly formed devices each having 110 one end adapted to engage the pintle and removably hold it in its slot. 115

4. In a typewriting machine, the combination with a curved bracket having a plurality of slots and provided with over-hanging 120 portions forming recesses at the sides of said slots, said bracket having threaded openings, of a plurality of type-bars having laterally projecting pintles adapted to be seated in said recesses, said recesses being 125 open transversely for the removal of the pintles and type-bars, angularly formed devices having a vertical movement and held to slide on said bracket one for each type-bar, the vertical portion of each device hav- 130

- ing its upper end slotted and beveled and adapted to span its coöperating type-bar and to engage the pintle on the under side thereof to hold the same in its recesses, a tongue 5 integral with each device and entering the slot beneath the type-bar and holding the same against lateral movement, said device having an opening therethrough, and a screw passing through said opening and en- 10 gaging one of the threaded openings in the bracket and adapted to detachably hold the device to said bracket to permit each type- bar to be independently removed.
5. In a typewriting machine, the combination with a bracket having a plurality of slots and provided with over-hanging portions forming recesses at the sides of said slots, of a plurality of type-bars having laterally projecting and independent pintles 20 adapted to be seated in said recesses, said recesses being open transversely for the removal of the pintles and type-bars, and angularly formed L-shaped devices held to slide on said bracket one for each type-bar, 25 the vertical portion of each device having its upper end slotted and adapted to span its coöperating type-bar and to engage the pintle to hold the same in its recess or bearing.
6. In a typewriting machine, the combination with a bracket having a plurality of vertical slots and provided with over-hanging portions forming recesses at the sides of said slots, of a plurality of type-bars hav-
- ing laterally projecting pintles adapted to be seated in said recesses, said recesses being open transversely for the removal of the pintles and type-bars, devices held to slide on said bracket one for each type-bar, the vertical portion of each device having its upper end slotted and adapted to span its coöperating type-bar and to engage the pintle on the under side thereof to hold the same in its recess or bearing, a tongue integral with each device and entering the slot beneath the type-bar to hold the same against lateral movement, and means for detachably holding the devices to said bracket to permit each type-bar to be independently removed.
7. In a typewriting machine, the combination with a bracket having a plurality of slots, of a plurality of type-bars pivotally held in said slots each with an independent pintle, said slots being open transversely for the removal of the pintle and type-bars, and angularly formed devices having one end adapted to span each type-bar and engage the pintle and hold it in its slot, and means for detachably holding said devices to the bracket.

This specification signed and witnessed this 4th day of June A. D. 1909.

OTTO PETERMANN.
